PAPER BOX FOLDING AND CORNER
LOCKING MACHINEFrank A. Bellato, Stockton, Calif., assignor to
Carando Machine Works, Stockton, Calif., a
partnership

Application February 23, 1951, Serial No. 212,237

6 Claims. (Cl. 93—51)

1

This invention is directed to, and it is a major object to provide, a novel machine for folding paper boxes from pre-cut blanks and then locking the corners of the boxes, all as an automatic progressive operation; the paper boxes being of the type which include a "hook and eye" connection between infolded tabs on the ends of the boxes and adjacent engaged portions of the sides of the latter.

Another important object of the invention is to provide a paper box folding and corner locking machine, as in the preceding paragraph, which includes an effective plunger and die assembly for folding the boxes from blanks; there being novel spring-pressed, cam-actuated, fingers arranged on the plunger in a manner to cause engagement of the "hook and eye" connections, adjacent the corners, after each box has been folded to shape.

A further object of this invention is to provide the aforesaid plunger and die assembly with novel cooperating cam elements for actuating the aforesaid fingers in proper timed relation to box forming motion of the plunger into the die; the fingers first serving to slightly out-bend the tongues in the sides so that the infolded end tabs may come to position inwardly thereof, and then said fingers act to snap the hook of said tabs through the eyes formed by the out-bend tongues.

An additional object of the invention is to provide a paper box folding and corner locking machine which is smooth, fast acting, and positive in operation.

Still another object of the invention is to provide a practical and reliable paper box folding and corner locking machine, and yet one which will be exceedingly effective for the purpose for which it is designed.

These objects are accomplished by means of such structure and relative arrangement of parts as will fully appear by a perusal of the following specification and claims.

In the drawings:

Fig. 1 is an end elevation of the machine; the plunger and die being separated, and a paper box blank being fed therebetween.

Fig. 2 is an enlarged side elevation of the plunger and die assembly; the die being in section, and a paper box blank being in position for plunger engagement.

Fig. 3 is an enlarged plan view of the plunger and die assembly, as in Fig. 2.

Fig. 4 is a fragmentary sectional plan of the plunger in association with the die; the plunger being advanced into the die in box-side folding position.

Fig. 5 is a similar view with the plunger further advanced to box-end folding position.

Fig. 6 is a similar view with the plunger still further advanced, with the fingers cam-actuated to couple the hook and eye connections.

Referring now more particularly to the characters of reference on the drawings, and at present to Fig. 1, the machine comprises an upstanding main frame, indicated generally at 1, and a guided, vertically reciprocable head 2 is mounted in the upper portion of said frame; the head 2 being reciprocated by a connecting rod 3 which extends downward to connection with a counterbalanced crank 4 on a driven shaft 5 journaled in the frame 1.

A heavy-duty suspension bar 6 is fixed to the head 2 and projects downward to rigid connection with the plunger, indicated generally at 7, of the plunger and die assembly which the machine embodies for forming or folding paper boxes from initially flat blanks.

The die, which is of open throat type, and indicated generally at 8, is fixed in the frame 1 in vertical alinement with the plunger 7 in a position such that when said plunger reciprocates, it thrusts downward, recurringly, through said die.

The assembly of the plunger 7 and die 8 embodies the essence of the present invention, and such assembly is hereinafter described in detail with respect to its structure and function.

In advance of each down-stroke of the plunger 7 a flat, pre-cut paper box blank 9 is fed, in located relation, onto the top of the die 8 by means of a pair of feed rolls 10 disposed along one side 35 of said die. One blank 9, as in Fig. 1, is in the course of feeding onto the die. The blanks 9 are placed initially on the machine in a stack 11 carried on an open support 12 laterally outwardly of, and somewhat above, the entry point of the feed rolls 10. The following mechanism is employed to deliver the blanks 9 from the bottom of the stack 11, one at a time and in proper timed relation, to the feed rolls 10.

A vertically reciprocable suction head 13 is 45 mounted on the upper end of a tubular post 14 directly beneath the stack 11. The tubular post 14 is carried on a vertically reciprocable column 15 linked at its lower end, as at 16, to one end of a vertically swingable lever bar 17; the latter being actuated by a cam 18 on the driven shaft 5.

The tubular post 14 is connected by a conduit 19 to a source of suction (not shown), and a valve 20 is interposed in such conduit, the valve 20 being actuated, in proper timed relation, by 55 a cam 21 on the driven shaft 5.

With each up-stroke of the column 15 and post 14, the suction head 13 engages and grips the lowermost blank 9 in the stack 11. As the suction head 13 begins its down-stroke, such lowermost blank is snapped through the open support 12 and deposited on a transversely spaced rail platform 22, whence such blank is fed by a horizontally reciprocated feeder 23 into the feed rolls 10 for delivery onto the die 8; such feeder 23 including an upstanding feed nub 24 which engages the blank at its rearmost edge in advancing relation.

The feeder 23 is connected, at the bottom, to a depending swing arm 25 actuated by a cam 26 on a shaft 27; the latter being driven from the shaft 5 through the medium of an intermediate shaft 28 and a gear train shown diagrammatically at 29.

The feed rolls 10 are driven from the shaft 28 by an endless drive 30, while said shaft 28 also serves to drive an endless conveyor 31 disposed with its upper run horizontal and in a position to receive formed boxes as discharged from the lower end of the die 8.

The plunger 7 and die 8 are shown in detail in Figs. 2-6, inclusive, and are constructed and function as follows:

The plunger 7 is comprised of a rectangular plunger block 32 which is horizontally disposed, and in plan matches the bottom 33 of the paper box formed from each blank 9. The flat blanks 9, which are pre-cut, comprise—in addition to the bottom 33—sides 34 and ends 35, defined from the bottom 33 by longitudinal scoring 36 and transverse scoring 37, respectively.

Additionally, the ends 35 are formed with initially laterally projecting end tabs 38 defined from the box ends 35 by longitudinal scoring 39, and from the box sides 34 by transverse splits 40.

In the formation or folding of each blank 9 to provide a shallow paper box, the sides 34 are first folded to a vertical position and then the box ends 35 are folded upward to vertical, with the end tabs 38 folded inwardly in overlapping relation outside the adjacent portions of the box sides 34. Such adjacent portions of the box sides 34 are pre-cut with V-slits 41 which point towards the corresponding end of the box; such V-slits 41 forming triangular tongues 42.

When said tongues are pushed slightly outwardly from the box sides 34, after the latter are folded upwardly, the resultant openings provide "eyes" for the reception—in holding relation—of hooks 43 formed in the corresponding andlapping end tabs 38 by diagonally splitting the latter, as at 44.

The die 8 includes a vertically open die throat 45 symmetrical to the plunger block 32 and of only slightly greater dimensions; such die throat 45 being defined by the side walls 46 and end walls 47 of said die.

Attachment flanges 48 lead in opposite directions from the end walls 47, whereby to mount the die in position in the main frame 1.

The side walls 46 are of substantially greater height than the end walls 47; the uppermost portions of the side walls 46 being formed as downwardly and inwardly sloping, box side folding flanges 49, while the uppermost portions of the end walls 47 are formed as downwardly and inwardly sloping, box end folding flanges 50. With this arrangement, the box side folding flanges 49 are some distance above the box end flanges 50.

As each flat blank 9 feeds onto the die 8, such blank is supported—along opposite longitudinal

edges—by the upper edges of the side walls 46, and such blank is located, endwise, by upstanding end guide plates 51 secured to the end walls 47 laterally out from the box end folding flanges 50.

The timing of the machine is such that after a flat blank 9 is delivered onto the die 8, the plunger 7 begins its down-stroke, engaging the blank 9 and pressing the same downwardly into the die 8.

As the blank is initially pressed into the die 8, the downwardly and inwardly sloping flanges 49 first bend the box sides 34 upwardly to vertical, and then the downwardly and inwardly sloping flanges 50, being in a lower plane, act to bend the box ends 35 upwardly to vertical. Similarly, the end tabs 38 ride down tab-fold lands 52 at the ends of the flanges 49; such lands being formed, and cooperating with the corresponding flanges 49, to cause the end tabs 38 to fold inwardly in lapping relation to the adjacent portions of the already up-folded box sides 34 as the box ends 35 are folded to their upright position.

The plunger block 32 has a longitudinal channel 53 in each side thereof, and a pair of flat, elongated fingers 54 are secured in each channel in the manner as will hereinafter appear; each pair of said fingers projecting out of the related channel 53 in widely diverging relation. The fingers 54 are each formed, at the outer end, with an out-turned tip 55, and said tips lead out of the corresponding channels 53 adjacent but short of the corresponding ends of the latter. The fingers 54, including the tips 55, are of spring metal.

The position of the finger tips 55 is such that when the plunger block 32 drives into the die 8 to fold the box sides 34 upwardly, said tips 55 engage the triangular tongues 42 from the inside and push said tongues outwardly, as in Fig. 4, to open the "eyes" formed by the V-slits 41. Consequently, upon further down-stroke of the plunger block 32, and when the box ends 35 are folded upwardly, and the end tabs 38 folded inwardly in lapping relation to the box sides 34, said tabs lie between the finger tips 55 and the adjacent portions of the box sides 34. (See Fig. 5).

The side walls 46 of the die are formed with vertical channels 56 to permit the tips 45 to push the tongues 42 outwardly, as above.

Upon still further motion of the plunger block 32 downwardly, the fingers 55 are caused to swing into the channels 53 by the mechanism which will hereinafter be described. When this occurs the tips 55 of the fingers pass through the "eyes" formed by the V-slits 41, and snap the corresponding hooks 43 through such "eyes," whereupon the end tabs 38 are effectively interengaged or hooked with the box sides 34. See Fig. 6.

The plunger block 32 then completes its down-stroke below the die 8, whence the completed box falls from the plunger block 32 onto the endless conveyor 31 for "carry-off." The plunger block 32 is formed with relief notches 57 in the bottom portion thereof and adjacent the corner, whereby the hook and eye connections between the end tabs 38 and box sides 34 may clear the die without obstruction.

The flat, elongated fingers 54 are mounted as follows, to the accomplishment of the above described action thereof:

Adjacent but short of the inner end thereof each finger 54 is attached by a screw 58 to the flat side of a vertical spindle 59 which is exposed in the related channel 53; each spindle extending

upwardly out of the plunger block 32 and being carried in a journal bracket 60. Beyond each spindle 59 each finger 54 is normally urged outwardly by a compression spring 61; such springs thus being the medium which maintain such fingers 54 in their normal position, with the tabs 55 projecting out of the channels 53 for the purpose described.

The fingers 54 and tips 55 are limited in outward motion under the influence of the springs 61 because the inner ends of said fingers engage stops 62 formed angularly in the channels 53.

At their upper ends the spindles 59 are fitted with radial arms 63 having horizontal-axis rollers 64 on their outer ends; the radial arms 63 being set so that the rollers 64 normally project laterally out from the vertical planes of the corresponding sides of the plunger block 32.

As the plunger block 32 reaches a relatively low position in the die 8, and at which point it is desired to swing the fingers 54 into the channels 53, as in Fig. 6, the rollers 64 engage corresponding, downwardly and inwardly sloping cam-ways 65 in the side walls 46 of the die. As the rollers 64 ride down the cam-ways 65, the spindles 59 are part-rotated in the correct direction to swing the fingers 54 into the channels 53 against the compression of the springs 51.

It will also be recognized that as the plunger block 32 escapes the bottom of the die 8 for the purpose of discharging the formed box onto the conveyor 31, the rollers 64 riding the side walls 46 of the die will maintain the fingers 54 in an out-of-the-way or non-obstructing position in the channels 53.

With the described machine, paper boxes are formed rapidly, positively, and smoothly; folding of the box sides, folding of the box ends and tabs, and the hook and eye connection of said tabs with the box sides, being accomplished in a wholly automatic and effective manner.

From the foregoing description it will be readily seen that there has been produced such a device as substantially fulfills the objects of the invention, as set forth herein.

While this specification sets forth in detail the present and preferred construction of the device, still in practice such deviations therefrom may be resorted to as do not form a departure from the spirit of the invention, as defined by the appended claims.

Having thus described the invention, the following is claimed as new and useful, and upon which Letters Patent are desired:

1. A mechanism for coupling hook and eye connections adjacent the corners of a paper box formed in a machine having an open throat die and a plunger to progress an initially flat, pre-cut paper box blank through the die to up-fold the sides and ends of the box and to in-turn end tabs of the box ends into outside lapping relation to adjacent portions of said sides, the tabs including hooks, and said adjacent portions of the sides being slit to form tongues which when pushed outward open eyes through which corresponding hooks are adapted to be engaged; said mechanism comprising normally protruding elements on the plunger in position to push the tongues outward and project through the eyes upon up-folding of the sides, the elements being mounted on the plunger for retraction, and a cam means in part on the plunger and in part on the die operative upon continued progress of the plunger through the die arranged to cause retraction of said elements, the retracting elements

drawing the corresponding hooks through said eyes for engagement therewith; a rotary spindle for each element on which the latter is secured, the spindle being journaled on the plunger lengthwise of the direction of travel of the latter, part turning of the spindle retracting the element; said cam means including a cam arm radiating from the spindle, and the die having a camway which said cam arm engages in spindle turning relation upon said continued progress of the plunger.

2. A mechanism for coupling hook and eye connections adjacent the corners of a paper box formed in a machine having an open throat die and a plunger to progress an initially flat, pre-cut paper box blank through the die to up-fold the sides and ends of the box and to in-turn end tabs of the box ends into outside lapping relation to adjacent portions of said sides, the tabs including hooks, and said adjacent portions of the sides being slit to form tongues which when pushed outward open eyes through which corresponding hooks are adapted to be engaged, the tongues extending lengthwise of the sides and remaining connected thereto at the ends opposite the box corners; said mechanism comprising flat thin fingers normally protruding from the sides of the plunger in outwardly diagonal relation and in position to push the tongues outward and project through the eyes upon up-folding of the sides, the fingers then extending generally along the tongues and the hooks of the in-turned tabs lying between said extending fingers and the eyes, means mounting the fingers on the plunger for inward swinging retraction, and means operative upon continued progress of the plunger through the die arranged to cause said retraction of the fingers whereby the latter sweep the corresponding hooks through said eyes for engagement therewith.

3. A mechanism, as in claim 2, in which the die is formed in a manner to cause up-folding of the box sides, and consequent projection of the fingers through the eyes, in advance of up-folding of the box ends and in-folding of said tabs, whereby the hooks of the tabs move to position between the fingers and eyes only after said projection of the fingers.

4. A mechanism for coupling hook and eye connections adjacent the corners of a paper box formed in a machine having an open throat die and a plunger to progress an initially flat, pre-cut paper box blank through the die to up-fold the sides and ends of the box and to in-turn end tabs of the box ends into outside lapping relation to adjacent portions of said sides, the tabs including hooks, and said adjacent portions of the sides being slit to form tongues which when pushed outward open eyes through which corresponding hooks are adapted to be engaged, the tongues extending lengthwise of the sides and remaining connected thereto at the ends opposite the box corners; said mechanism comprising flat fingers normally protruding from the sides of the plunger in outwardly diagonal relation and in position to push the tongues outward and project through the eyes upon up-folding of the sides, the fingers then extending generally along the tongues and the hooks of the in-turned tabs lying between said extending fingers and the eyes, means mounting the fingers on the plunger for inward swinging retraction, said mounting means for each finger including a rotary spindle journaled on the plunger lengthwise of its direc-

tion of travel, part-turning of the spindle reTRACTING said finger, a radial cam member on the spindle, and cooperating cam-way on the die which the cam member engages in spindle turning relation upon continued progress of the plunger through the die, whereby each finger is reTRACTED and sweeps the corresponding hook through the adjacent eye for engagement therewith.

5. A mechanism for coupling hook and eye connections adjacent the corners of a paper box formed in a machine having an open throat die and a plunger to progress an initially flat, pre-cut paper box blank through the die to up-fold the sides and ends of the box and to in-turn end tabs of the box ends into outside lapping relation to adjacent portions of said sides, the tabs including hooks, and said adjacent portions of the sides being slit to form tongues which when pushed outward open eyes through which corresponding hooks are adapted to be engaged, the tongues extending lengthwise of the sides and remaining connected thereto at the ends opposite the box corners; said mechanism comprising flat fingers normally protruding from the sides of the plunger in outwardly diagonal relation, the sides of the plunger having longitudinal channels in which the inner portions of the fingers are disposed and into which channels the whole of the fingers are adapted to swing, means pivotally mounting the fingers in said channels for inward swinging retraction thereinto, spring means resisting such retraction, the normally protruding fingers being in position to push the tongues outward and project through the eyes 35

upon up-folding of the sides, the fingers then extending generally along the tongues and the hooks of the in-turned tabs lying between said extending fingers and the eyes, the pivots for the fingers being rotary spindles, and cooperating cam means between the plunger and die arranged to part-turn the spindles in a direction to swing the fingers wholly into said channels upon continued progress of the plunger through the die, whereby said fingers sweep the tongues through the eyes for engagement therewith.

6. A mechanism, as in claim 5, in which the spindles extend lengthwise of the direction of motion of the plunger, the spindles having portions exposed in the channels, means securing the fingers adjacent but short of their inner ends to the said portions, outwardly facing stops against which the inner ends of the fingers abut, and springs in the channels engaging the fingers therein and urging said fingers outward at their outer ends.
